UNITED STATES PATENT OFFICE.

MELNOTTE G. POLK, OF BROOKLYN, NEW YORK.

COLLAR ATTACHMENT.

986,755.

Specification of Letters Patent. Patented Mar. 14, 1911.

Application filed July 22, 1910. Serial No. 573,348.

To all whom it may concern:

Be it known that I, MELNOTTE G. POLK, a citizen of the United States, residing at Brooklyn, in the county of Kings and State 5 of New York, have invented new and useful Improvements in Collar Attachments, of which the following is a specification.

This invention relates to improvements in collars and has particular reference to an 10 attachment coöperating with the neckband of a shirt, whereby the rear portion may be secured to the neckband of a shirt without the employment of the ordinary button.

A further object is the provision of an 15 attachment which may be applied to most forms of standing collars now in use without in any way altering the shape of the collar or forming an abutment to prevent endwise movement of the tie.

20 With these and other objects in view, which will more fully hereinafter appear, the present invention consists in certain novel details of construction and arrangement of parts, hereinafter fully described, 25 illustrated in the accompanying drawings and more particularly pointed out in the appended claims; it being understood that various changes in the form, proportion, size, and minor details of the devices may 30 be made, within the scope of the appended claims, without departing from the spirit or sacrificing any of the advantages of the invention.

In the accompanying drawings, forming 35 part of the specification;—Figure 1 is a perspective view of a collar provided with my improved device and also showing a portion of a neckband of a shirt engaged thereby. Fig. 2 is a front elevation of a collar provided with my improved device and showing the appearance of the same before bending. Fig. 3 is a vertical section taken on the line 3—3 of Fig. 1.

The device is particularly applicable to 40 the neckbands of negligée shirts wherein a pocket is usually provided at the middle or rear side of the band and for purposes of illustration I have shown the neckband of such a garment, it being understood, however, that I am not to be limited to the employment of the device with this specific 45 form of neckband since it will be readily understood from what will appear later how the device might be readily secured to a

neckband divided at the front and rear and 55 provided with a pocket at the rear.

The neckband includes an outer ply 5 and an inner ply 6. These flaps are secured together at their lower edges by stitching 7, the said stitching extending from points 60 equi-distant from the middle of the band to the ends thereof and it will be manifest with this construction when the upper edges of the flaps are secured by a continuous row of stitching that a pocket will be formed, the 65 opening of which will be located between the ends of the stitching 7 and the central portion of the band.

The collar is designated in general by the numeral 8 and in the present instance is 70 shown to be of the ordinary turn-down type, it being understood that this particular type is shown merely for purposes of illustration, since it will be seen from what will appear later how the device about to be described might be equally as well employed 75 with other types of collars.

By reference to the drawings it will be seen that the collar 8 is medially provided 80 with a tab, the said tab including in its construction a neck 9, which depends from the lower edge of the collar and may be of the same material as the collar or other bendable substance. The neck terminates in a body 10, which in the present instance is shown 85 to be of greater length than the width of the neck and is preferably formed integral therewith. The width of the neck 9 corresponds approximately to the length of the opening 90 of the pocket, while the length of the body 10 is considerably greater than the opening of the pocket so that when the neck is bent upwardly and the body arranged over the inner face of the collar, the said body may be inserted into the pocket by first inserting 95 one end portion thereof into the opening of the pocket and thence bending the opposite end portion and inserting the same through the opening of the pocket, whereupon the end portions will bear on the lower side of 100 the pocket thus preventing accidental displacement of the device.

From the foregoing, it is evident that I have provided a device which is comparatively simple in structure and inexpensive 105 in manufacture, embodying few parts and these so arranged that the danger of derangement will be reduced to a minimum.

I claim:

The combination with a neckband of a shirt having outer and inner plies stitched together on one edge from points equi-distant from the middle of the band to provide a pocket, of a collar having a continuous lower edge and a tab including a bendable neck portion depending from the lower side of the collar and terminating in a bendable body portion insertible into the pocket, said

body portion being greater in length than the width of the neck and also of greater length than the opening of the pocket.

In testimony whereof I affix my signature in presence of two witnesses.

MELNOTTE G. POLK.
